UNITED STATES PATENT OFFICE.

JAMES B. REPLOGLE, OF DETROIT, MICHIGAN, ASSIGNOR TO THE REMY ELECTRIC COMPANY, A CORPORATION OF INDIANA.

CENTRIFUGAL CUT-OUT.

1,402,445.

Specification of Letters Patent.

Patented Jan. 3, 1922.

Application filed April 15, 1918. Serial No. 228,668.

To all whom it may concern:

Be it known that I, JAMES B. REPLOGLE, a citizen of the United States of America, residing at Detroit, in the county of Wayne 5 and State of Michigan; have invented certain new and useful Improvements in Centrifugal Cut-Outs, of which the following is a full, clear, and exact description.

This invention relates to automatic circuit-breaking devices or cut-outs, and more particularly to cut-outs of the centrifugal type in which an electric circuit may be opened or closed in accordance with the speed of a rotating member with which the cut-out is 15 associated.

One of the objects of the present invention is to provide a centrifugal cut-out having a centrifugal device which may be mounted as a unit upon a rotating shaft or other 20 rotating member.

Another object of the present invention is to provide a centrifugal cut-out which may be attached to any device having a rotatable element, although the said device 25 may not have been originally constructed so as to include a centrifugal cut-out.

Other and further objects and advantages of the present invention will be apparent from the following description, reference being had to the accompanying drawings, 30 wherein a preferred embodiment of the present invention is clearly shown.

In the drawings:

Fig. 1 is a plan view of the centrifugal device included in the present invention, the centrifugal elements being in closed position;

Fig. 2 is a plan view similar to Fig. 1, but with the centrifugal elements in opened position;

Fig. 3 shows a sectional view of the centrifugal elements and a side elevation of the switch elements included in the present invention, said switch elements and centrifugal device being applied to a generator which is shown in a wiring diagram in circuit with a storage battery and certain electrical translating devices; and

Fig. 4 is a sectional view of the generator shaft taken on line 4—4 of Fig. 3.

Referring to Fig. 3, 20 designates a generator having an armature shaft 21, adapted to be driven by any convenient source of power, not shown, and provided at one end 55 with a groove 22 adapted to receive a tongue

23 of the hub 24 forming a part of the centrifugal device. The tongue 23 cooperates with the groove 22 so that a driving connection will be formed between the armature shaft and the centrifugal device. The hub 60 24 is secured axially of the shaft 21 by means of screw 25, which passes through the hub 24 and has threaded engagement with the shaft 21. Upon the hub 24 there is fixed a base plate 26, and the said hub is provided 65 with an extension 27 which provides a journal, upon which is mounted for rotation an equalizer 28. Plate 26 carries pivoted posts 29, upon which are mounted for oscillation centrifugal elements 30 which carry pins 31 70 engaging slots 32 formed in the equalizer 28. Plate 26 is provided with slots 33, into which the pins 31 may project. The centrifugal elements 30 are provided with beveled camming surfaces 34 which, together, form a 75 polyhedron, or a polyhedral angle, the apex of which is located on the center line of the shaft 21. The surfaces 34 are provided with recesses 35 to provide a clearance space for a purpose to be described. The plate 26 carries spring posts 36 to which are connected one end of springs 37 having their other ends connected to bent-up ears 38 formed on equalizer 28.

40 designates a cup-shaped cover, designed 85 to be secured in place upon spring posts 36 by means of screws 39 having threaded engagement therewith. Said cover 40 is designed to inclose the edges of plate 26 and the elements supported by plate 26. The 90 plate 40 is provided with a central aperture surrounded by flange 41, which projects into the space formed by recesses 35. A ball 42 is located in the polyhedral angle included by surfaces 34, and said ball is shown in 95 Fig. 3 in contact with said surfaces 34, and with the flange 41 of cover 40, which serves to limit the outward movement of ball 42 by virtue of the outer portion of said flange 41 being slightly smaller in diameter than the 100 diameter of said ball.

Switch element 43 is mounted upon generator 20, but insulated therefrom, and carries contact 44 which cooperates with contact 45, carried by switch element 46 of resilient material which is mounted upon the bracket 48 supported by generator 20 but insulated therefrom. Contact element 46 carries a button 47 of insulating material which contacts with the ball 42. 110

In the wiring diagram shown in Fig. 3, the generator 20 is shown in circuit with the storage battery 50, the charging circuit being as follows: from the battery 50, 5 through wire 51 to terminal 52 of the generator, through the generator windings, out through terminal 53, through wire 54 to switch terminal 55, through members 48, 46, contact 45, contact 44, member 43, terminal 10 56, and wire 57 to the battery 50. Electrical translating devices may be connected with the battery and generator by means of wires 58 and 59, and said devices may include lamps 60 and an ignition system including 15 ignition coil primary winding 61, timer 62, and the secondary winding 63 of the ignition coil which is grounded at 64 and connected by means of wire 65 with the distributor 66, which is connected by means of conductors 20 67 with the various spark plugs of an internal-combustion engine, not shown.

The operation of the device is as follows:

When the generator armature shaft 21 is at rest, the centrifugal elements will be in 25 the position shown in Figs. 1 and 3, and, when in this position, the ball 42 will be forced outwardly by the camming surfaces 34 of elements 30, into contact with the button 47 and thereby cause the outward movement 30 of the contact 45 and the separation of contacts 44 and 45. When this condition is present, the circuit from the battery through the generator is broken. When the shaft 21 starts to rotate, the centrifugal members will 35 begin to separate, and, when the armature shaft 21 has attained normal speed, the centrifugal elements 30 will reach the position shown in Fig. 2. When the elements 30 are in this position, the ball 42 will have moved 40 inwardly toward the plate 26, through the action of the spring contact carrying element 46, and will have reached the dotted line position touching the end of hub 24 as shown in Fig. 3. When these conditions 45 are present, the contact 45 will be permitted to engage the contact 44 and the electrical circuit between the generator and the battery will be established. When the armature shaft 21 is rotating at normal speed, the 50 centrifugal elements 30 will overcome the tension of springs 37 and cause, by virtue of the pin and slot connections 31 and 32, a movement of the equalizer 28. The equalizer is constructed with relation to the 55 centrifugal elements so that centrifugal force acting on said elements will be transmitted by each of the pins 31 to the equalizer 28 and will be distributed equally between the springs 37 to elongate the same. As the 60 speed of the shaft 21 decreases, centrifugal force acting on elements 30 will decrease in proportion, and when a certain point in the decrease in speed has been attained, the springs 37 will overcome the centrifugal 65 force acting on elements 30, causing said ele-

ments to take the position shown in Figs. 1 and 3, thus causing the ball 42 to be cammed outwardly against the action of the spring contact element 46, and to cause the separation of contact elements 44 and 45. The 70 equalizer 28, by reason of the pin and slot connection with each of the centrifugal elements 30, insures equality of the movements of each of said elements toward or away from the center of rotation. Therefore the 75 ball 42 may cooperate equally with the three camming surfaces 34 of elements 30 in order to transmit motion imparted by said elements in the proper directions axially of the shaft 21.

While the present invention has been shown as applied to a battery charging system, it is to be understood that the application is not thus limited, but that the present invention may be applied to other devices 85 including a rotatable element, and where it is desired to make or break an electric circuit in response to the change in speed of the rotatable element.

While the form of mechanism herein 90 shown and described constitutes one preferred form of embodiment of the invention, it is to be understood that other forms might be adopted, all coming within the scope of the claims which follow.

What I claim is as follows:

1. In a centrifugal cut-out, the combination with cooperating contact members; of a centrifugal device adapted to be mounted on a shaft for rotation therewith including 100 a plurality of centrifugal members, an equalizer element cooperating with the centrifugal members, and means adapted to cooperate equally with all the centrifugal members to impart motion to certain of the 105 contact members.

2. In a centrifugal cut-out, the combination with cooperating contact members; of a centrifugal device adapted to be mounted on a shaft for rotation therewith including 110 a plurality of centrifugal members, an equalizer element cooperating with the centrifugal members, yielding means acting to oppose the action of centrifugal force upon the centrifugal members, and a member 115 cooperating with the centrifugal members to impart motion to certain of the contact members.

3. In a centrifugal cut-out, the combination with cooperating contact members; of a centrifugal device adapted to be mounted 120 on a shaft for rotation therewith including a plurality of centrifugal members each provided with a camming surface, an equalizer element cooperating with the centrifugal members to effect equality of movement of the camming surfaces, and means adapted to cooperate equally with all the camming surfaces to impart motion to certain of the contact members.

4. In a centrifugal cut-out, the combination with cooperating contact members; of a centrifugal device adapted to be mounted on a shaft for rotation therewith, including 5 a plurality of centrifugal members, a single equalizer element cooperating with the centrifugal members, yielding means cooperating with the equalizer to oppose the action of centrifugal force on the centrifugal members, and a member cooperating with the centrifugal members to impart motion to certain of the contact members.
5. In a centrifugal cut-out, the combination with cooperating contact members; of 15 a centrifugal device adapted to be mounted upon a shaft for rotation therewith, and including centrifugal members mounted in eccentric relation to the shaft and to oscillate in a plane transverse to the shaft, and 20 axially mounted equalizer cooperating with the centrifugal members, yielding means cooperating with the equalizer to oppose the action of centrifugal force on the centrifugal members, and a member cooperating directly 25 with the centrifugal members to impart motion to certain of the contact members.
6. In a centrifugal cut-out, the combination with cooperating contact members; of a centrifugal device adapted to be mounted 30 upon a shaft for rotation therewith, and including centrifugal members provided with camming surfaces, a single member only with which said surfaces cooperate for transmitting motion from the centrifugal 35 elements to certain of the contact members, and means for guiding the last mentioned member.
7. In a centrifugal cut-out, the combination with cooperating contact members; of 40 a centrifugal device adapted to be mounted upon a shaft for rotation therewith, and including centrifugal members provided with camming surfaces which together include a polyhedral angle, a ball located in 45 said angle and touching said camming surfaces, and adapted to transmit motion from the centrifugal elements to certain of the contact members, and a member having a circular flange for guiding the ball.
- 50 8. In a centrifugal cut-out, the combination with cooperating contact members; of a centrifugal device adapted to be mounted upon a shaft for rotation therewith, and including a base plate adapted to be attached 55 to said shaft; centrifugal members pivotally mounted on the base plate and provided with camming surfaces which together include a polyhedral angle; an equalizer
- movable on the base plate and cooperating with the centrifugal spring members connected with the base plate and with the equalizer; a cover having an edge flange secured on the base plate and cooperating therewith to form an inclosure for the parts supported by the base plate, said cover also 60 having a central aperture surrounded by a flange; and a ball of slightly larger diameter than the central aperture of the base plate located in the said polyhedral angle and adapted to be moved by the camming surfaces of the centrifugal members and to transmit motion therefrom to certain of the contact members, said ball being 65 guided by the flange surrounding the central aperture of the base plate and being 70 limited thereby in movement in one direction.
9. In a centrifugal cut-out, the combination with a rotatable shaft; of a switch including a movable member located opposite 80 an end of said shaft; and a centrifugal device carried by said shaft including a ball located in axial alignment with said shaft, pivotally mounted weight members each having a beveled camming surface located 85 on the same side of the pivot as the center of mass of the weight member, said camming surfaces together defining a polyhedral angle in which the ball is located, and spring means restraining outward movement of 90 said weight members whereby said ball is pressed against the switch member when the shaft is stationary.
10. In a centrifugal cut-out, the combination with a rotatable shaft; of a switch 95 including a resilient movable member tending to engage a second switch member, and located opposite an end of said shaft; and a centrifugal device carried by said shaft, including pivotally mounted weight members each having a beveled camming surface located on the same side of the pivot as the center of mass of the weight member, said camming surfaces together defining a polyhedral angle, a ball located in said angle 105 and spring means yieldingly maintaining said camming surfaces in proximity whereby said ball is pressed against said movable contact member and said member is pressed out of engagement with the second switch 110 member.

In testimony whereof I affix my signature.
JAMES B. REPLOGLE.
